(57) **CLAIM**

The ornamental design for an in-vehicle and shipboard amplifier, as shown and described.

DESCRIPTION

FIG. 1 is a front and bottom perspective view of an in-vehicle and shipboard amplifier showing my new design;

FIG. 2 is a front and top perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines shown are included for the purpose of illustrating the unclaimed portions of the article and form no part of the claim.
